UNITED STATES PATENT OFFICE

FRANK JULIAN SPRAGUE, OF NEW YORK, N. Y.

TRAIN CONTROL

Application filed June 12, 1928. Serial No. 284,801.

My invention relates to train control systems and more particularly to the disposition of trackway devices and their cooperation with car-carried train control apparatus used in train control systems of the intermittent inductive type.

Various arrangements of the trackway devices have been suggested for such systems in the past, one being fully disclosed in my 10 British Patent 149,922. In said patent use is made of track elements of two varieties, namely, "application" track elements, which transmit impulses to actuate or initiate actuation of normally inactive vehicle-carried 15 train control apparatus and "reset" track elements, which transmit impulses to restore or permit restoration of the train control apparatus after their actuation.

In the patent just referred to both the application 20 and the reset track elements are traffic controlled, and the primary object of my present invention is to provide for track elements of such character and disposition that traffic control is required for one kind of track element only.

Another object of my invention is to provide for trackway devices which transmit an impulse at every control point, irrespective of traffic conditions, and thereby initiate actuation 30 of the vehicle-carried apparatus, and check the integrity of the application track elements as well as of the translating device of the vehicle-carried apparatus every time a vehicle passes a control point, but cause automatic brake application only if adverse traffic conditions exist ahead of the train 35 when the control point is passed.

Other objects and advantages of my invention shall appear as the description progresses 40 and shall be particularly pointed out in the appended claims.

Referring to the accompanying drawing in which corresponding parts are designated by similar marks of reference:—

45 Figure 1 is a diagrammatic representation of a control system illustrating my invention; at the bottom of the figure a track is shown with trackway instrumentalities illustrating one form of my invention; above this are 50 shown the vehicle-carried parts.

Fig. 2 is a diagrammatic illustration of a track with trackway instrumentalities showing another form of my invention and also indicating the receiver of the vehicle apparatus.

Fig. 3 is a diagrammatic showing of the receiver of Figs. 1 and 2 on a larger scale.

Fig. 4 is a schematic diagram illustrating time delay means employable with my apparatus.

Referring to Fig. 1 there is shown a section of a railroad track divided by insulated joints 1 into blocks in the usual manner. Each block is provided with a track relay 2 at one end, and a source of energy, which has been illustrated as a battery 3, at the other end.

Placed near the end of each block is a permanently active application track element A 70 closely followed by a traffic controlled reset track element R.

As illustrated in Fig. 1, the application track element is a permanent magnet 4 with soft iron pole pieces 5 and the reset track element is an electro-magnet with a coil 6, a core 7 and pole pieces 8—8. The energizing circuit for the reset magnet R includes a battery 9 and a contact 10 controlled by the track relay 2. It should be understood that the herein presented simple form of traffic control for the energizing circuit of the reset magnets is merely indicative, and that as a rule such control requires additional instrumentalities and more involved circuit arrangements. As the organization of such circuits and instrumentalities is well known in the art, a simple showing has been selected here for clearness of understanding, thereby also omitting all instrumentalities which as, for instance, wayside signals, may be adjunct to the train control system.

Suitably carried on the vehicle is a double receiver D comprising an "application" and a "reset" portion, these portions being disposed in such angular positions as to cooperate with the respective track magnets, and will be hereafter referred to as the application receiver and the reset receiver. While these two receivers are here shown combined 100

in a single structure, they are independent of each other and, if so desired, may constitute separate units.

The application receiver consists of a portion 11-12 of magnetic material, interrupted by a gap 20, and provided at its two ends with collector plates 13-13. Projections 20'-20' of the portion 11-12 form poles in close proximity whereof is pivoted a spring retracted armature 15.

The reset receiver comprises a portion 16-17 of magnetic material, interrupted by a gap 21 and provided at its two ends with collector plates 18-18. Projections 21'-21' of the portion 16-17 form poles in close proximity whereof is pivoted a spring retracted armature 19.

To perpetuate an impulse received from the track and to govern further train control apparatus, there is provided a normally energized stick relay S. The maintaining circuit of this relay includes the stick-armature 26 of the relay S, and the application armature 15. The circuit can be traced as follows:

From the plus side of a battery 22, (or any suitable source of electric energy), through a wire 23, contact 15' and armature 15 of the application receiver, a wire 24, stick-armature 26, and contact 27 thereof, a wire 28, coil 29 of relay S, and a wire 30 back to negative battery.

The further train control apparatus is represented by a device K shown as a normally energized electromagnet, the energizing circuit of which is controlled by an armature 35 of the stick relay. The device K may be, in a simple train control system a device, de-energization of which directly results in an automatic brake application, or in a more complete system, it may represent a device which merely governs further train control apparatus; thereby the brake applying means effecting the automatic brake application may be either the standard engineer's valve or a separate brake valve.

Irrespective thereof, if the magnet K is the brake controlling device proper, or only an intermediate device, I provide a time delay between the de-energization of the magnet K and the actual application of the brakes (or other actuation of the train control apparatus tending to restrict the movement of the vehicle). Such time delay may be obtained by pneumatic, magnetic, or other suitable means. As an exemplification of such time delay means there is shown in Fig. 4 a device K' which comprises an electro-magnet E having a coil 50 surrounded by an iron cylinder 51 and a plunger type armature 52 which is preferably of conical shape.

Slackly suspended on the plunger 52 is a piston 53 moving within a hollow cylinder 54 which is integral with or forms an extension of the cylinder 51. A small bore 55 going through the piston 53 provides for the slow

equalization of the air pressure below and above the piston as the precise fit of the piston 53 in the cylinder 54 practically prevents communication between the space above and below the piston 53 along this piston.

The cylinder 54 is closed on its bottom by a disc 60 which carries a spring contact 61 and a cooperating top contact 62, the contacts 61 and 62 being provided with leads 63 and 64 going through the disc 60. The piston 53 carries a stop 65.

When the magnet K' is energized the plunger 52 is attracted and the piston 53 lifted. The spring contact 63 contacts against the contact 62 and closes the circuit of a second electro-magnet K-2 through the battery 22 or any other suitable source of supply.

The electro-magnet K-2 is now the brake-controlling device proper, upon de-energization of which the brakes are immediately applied.

Whenever the electro-magnet K' is de-energized the piston 53 drops slowly as it compresses in its descent the air underneath, as the pressure on the two sides of the piston can only gradually equalize through the bore 55. By suitably dimensioning bore 55 time delays of a fraction of a second to several seconds may be obtained.

The energizing circuit of the device K is as follows:

From plus battery through a wire 31, coil 32 of the device K, a wire 33, contact 34 and armature 35 of the relay S back to negative battery.

There are also two normally open circuits shown in Fig. 1. One circuit hereafter referred to as the reset circuit, goes from plus battery through wire 23 to the reset armature 19, is broken at a contact 19' (cooperating with armature 19) from where it can be traced through a wire 36, coil 29, and wire 30, to negative battery.

The other normally open circuit goes from plus battery through a wire 37 to an indicating device 38 (which may be visible or audible, or both), and from there through a wire 39 to a back contact 40 of armature 35; this circuit is completed to the negative side of the battery, when, the armature 35 is in its down position due to de-energization of the stick relay.

The device K may also be under the control of further car-carried apparatus as, for instance, of speed operated contacts. This is indicated in Figure 1 in dotted lines, where a speed operated contact 45 is placed in multiple to the contact 35 of the stick relay. A centrifugal speed governor 46 is indicated as controlling the armature 45. When the armature 35 drops upon receipt of a track impulse, the energizing circuit of the device K is maintained through contact 45 provided the speed of the train is below a set limit.

Instead of providing a time delay between the de-energization of the device K and the actuation of the brakes (or other train control apparatus) a time interval may be provided between the de-energization of the stick relay S and the de-energization of the device K, which can be obtained for instance by making the control armature 35 slow-acting.

In this case, however, the indicating device 38 should be controlled by another armature than the slow-acting armature 35 to display the indication immediately upon receipt of the track impulse.

Operation.—When a train reaches the end of a block, it first passes a permanent application magnet A. An application impulse is thereby transmitted from the track—irrespective of traffic conditions—which causes the poles 20'—20' to attract the armature 15 and to intermittently break the contact 15—15' in the maintaining circuit of the stick relay S. When the magnet is passed the spring returns the armature 15 to its normal position.

However this intermittent break of contact 15—15' causes de-energization of the stick relay S and dropping of the armatures 26 and 35. The armature 26 breaks the maintaining circuit of the stick relay at a second point and prevents it from being re-established, when, after the application magnet has been passed contact 15—15' recloses. Dropping of the armature 35 breaks the circuit of the device K and at the same time completes the circuit of the indicating device 38.

If the controlling zone of the subsequent reset magnet R (which may extend one or more blocks) is unoccupied, the traffic controlled armature 10 is closed and the reset magnet energized. A reset impulse is transmitted upon passage of the train which causes poles 21'—21' to attract reset armature 19, and to close intermittently the reset circuit. This re-energizes the stick relay S and the device K. After the reset magnet is passed the armature 19 is again retracted by its spring so as to open the contact 19—19'.

The distance between the application magnet A and the subsequent reset magnet R and the time interval between the de-energization of the stick relay and the start of a brake application (or other control functions initiated through de-energization of the device K) are so proportioned, that even at the lowest speed, the reset magnet is passed and the reset impulse transmitted before an automatic brake application (or other actuation of the train control apparatus) would take place.

Should, however, the control zone of the reset magnet be occupied the traffic controlled armature 10 will be open, and the reset magnet R thus de-energized; the application impulse not being now followed by

a corresponding reset impulse, the automatic brake application (or other actuation of the train control apparatus) initiated by the de-energization of the device K will take effect.

If the car-carried apparatus represents a plain automatic stop equipment, I also provide a reset switch 43 or similar device (preferably one requiring the train to stop for its operation) to restore the apparatus to normal when, after an automatic brake application, the train comes to a stop without passing an energized reset magnet. In case of speed control the reset device may be omitted.

It should be also noted that my invention can be readily applied to the various schemes of forestalling used in permissive train control systems.

In Fig. 2 I have shown another embodiment of my invention, whereby the application track element is traffic controlled and the reset element permanent, the traffic controlled track element again succeeding the permanent track element.

The application track element is shown as a compound magnet A', comprising permanent magnet bars 4', soft iron working poles 5'—5' and a neutralizing or cancelling coil 44. Such compound magnets are well-known in the art, one construction being fully described in my British Patent No. 149,922.

The energizing circuit of the coil 44 includes the same elements and is controlled in the same way as the circuit of the coil 6 of reset magnet R in Figure 1.

When the control zone of magnet A' is occupied, contact 10 is open, coil 44 is de-energized and the flux of the permanent magnet 4' fully effective. When the track is unoccupied the contact 10 is closed, coil 44 energized and the flux of the permanent magnets so diverted as not to have effect on the application receiver of a passing train.

The reset magnet R' consists of a permanent magnet 7' and soft iron pole pieces 8'—8'.

In this scheme the reset magnet R' will have no effect on a train running with the equipment in a normal condition, neither will the application magnet A' in case the track ahead is clear and the cancelling magnet 44 energized.

Should, however, the track ahead be occupied, the coil 44 is de-energized and an application impulse is transmitted to the passing train which causes de-energization of the stick relay S and of the device K, in the manner previously described.

If the train now passes a reset magnet the stick relay and the device K will be re-energized which restores or permits manual restoration of the brake applying means, unless the track ahead is still occupied, in which case the reset impulse will be closely followed

by an application impulse, again de-energizing the relay S and device K.

It should be noted that this lay-out of the track devices is more suited for speed control systems, than for plain automatic systems.

5 Furthermore, the time delay between de-energization of the device K and an automatic brake application can be dispensed with in this scheme.

To differentiate between the action due to the track elements of one character from the action due to the track elements of the other character, I have placed the application track elements and the reset track elements and the corresponding parts of the receiving device in various angular positions, but I do not want to limit my invention to such showing as the same object can be accomplished in other ways as, for instance, by placing one kind of track element closer to one rail than the other kind of track element, and by similarly off-setting the corresponding receiving devices.

While I have illustrated the traffic controlled track elements as being normally energized, in practice it is preferable to establish the energizing circuit only upon approach of the train. Such arrangement is well-known in the art and it is not deemed necessary to illustrate it.

30 In the same way while I have indicated my invention as applied to a double track system with track control only for one direction of traffic, my invention can be equally well applied to single tracks with traffic in both directions. In this case a permanent track element is both preceded and followed by a traffic controlled track element and for each direction of travel the control rests with the second traffic controlled track element.

It is obvious that various modifications can be made of my system without departing from the spirit of the invention. Therefore, without limiting myself to the details shown in this specification, what I claim and desire to secure by Letter Patents is:

1. In an inductive train control system, the combination of permanently active trackway elements followed in close succession by traffic controlled track elements, said two kinds of track elements being in different angular positions relative to the rails and located within the rails with vehicle-carried apparatus, said apparatus being inversely influenced by said trackway elements, whereby one kind of trackway element initiates operation of the vehicle-carried apparatus and the other kind of trackway element restrains operation thereof.

2. In an inductive train control system, a pair of track elements in close succession, the first track element being permanently active and the second element traffic controlled, the two track elements being disposed in different angular positions relative to the rails and

centrally located within the rails, effectiveness of an impulse transmitted by the permanent track element being dependent upon an impulse transmitted from the traffic controlled track element.

3. In an inductive train control system, two trackway elements in close succession and in different positions relative to the rails, the first track element acting independently of traffic conditions, the second track element 75 traffic controlled, and locomotive apparatus including a compound receiver to cooperate with both track elements whereby an impulse of the first track element is subject to nullification by an impulse of the second track element.

4. In an automatic train control system of the intermittent inductive type, a pair of trackway devices to transmit two kinds of impulses the members of the trackway devices being disposed in close succession centrally between the rails and in different angular relation thereto and car-carried apparatus comprising automatic brake applying mechanism and means to render one kind of track impulse effective to cause an automatic brake application unless said impulse is followed by an impulse of the second kind within a predetermined time interval.

5. In an inductive train control system in combination trackway means comprising a permanently active application track element closely followed by a traffic controlled reset track element, said two kinds of track elements being disposed centrally between the rails and in different angular relation thereto and train control apparatus comprising automatic brake applying means, actuation of said apparatus being initiated every time an application track element is passed, 90 said initiation resulting in an automatic brake application only in case of adverse traffic conditions.

6. In an inductive train control system, trackway devices comprising a permanent application magnet closely followed by a traffic controlled reset magnet, said two kinds of magnets being disposed in different angular relations to the rails and vehicle-carried apparatus comprising a unitary receiver adapted to cooperate with both track magnets, whereby the effectiveness of an impulse of the application magnet is subject to nullification by an impulse of the reset magnet.

7. In an automatic train control system, 125 trackway elements comprising a permanent application magnet closely followed by a traffic controlled reset magnet, said two kinds of magnets being disposed in different angular positions relative to the rails and centrally between the rails, and cooperating car-carried apparatus comprising an indicating device and brake applying means, said indicating device being always actuated by an impulse of the application magnet, actuation 130

of the brake applying means being preventable by an impulse of the reset magnet.

8. In an inductive train control system the combination of permanently active track elements followed in close succession by traffic controlled track elements, said two kinds of track elements being disposed centrally between the rails and in different angular relations towards the rails, with vehicle-carried apparatus, said apparatus being inversely influenced by said trackway elements whereby the first trackway element always restores the equipment to normal and the second kind of track element initiates operation thereof in case of unsafe traffic conditions.

9. In an inductive train control system, the combination of permanently active trackway elements followed in close succession by traffic controlled track elements, said two kinds of track elements being in different angular positions relative to the rails, with vehicle-carried apparatus comprising a single receiver unit influenced by each kind of trackway element, whereby one kind of trackway element initiates operation of the vehicle-carried apparatus and the other kind of trackway element restrains operation thereof.

Signed at New York, N. Y., this 11th day of June, 1928.
